UNITED STATES PATENT OFFICE.

HOWARD D. COLMAN, OF ROCKFORD, ILLINOIS, ASSIGNOR, BY MESNE ASSIGNMENTS, TO HIMSELF, LUTHER L. MILLER, AND HARRY A. SEVERSON, COPARTNERS DOING BUSINESS AT ROCKFORD, ILLINOIS, AS BARBER-COLMAN COMPANY.

METHOD OF TREATING WARP-THREADS.

1,129,849.

Specification of Letters Patent.

Patented Mar. 2, 1915.

Original application filed October 24, 1894, Serial No. 526,856. Continuation of applications filed September 6, 1902, Serial No. 122,381, and May 18, 1906, Serial No. 317,547. Divided and this application filed December 19, 1906. Serial No. 348,645.

To all whom it may concern:

Be it known that I, HOWARD D. COLMAN, a citizen of the United States, residing at Rockford, in the county of Winnebago and 5 State of Illinois, have invented a certain new and useful Method of Treating Warp-Threads, of which the following is a specification.

This application is a division of my application, Serial No. 317,547, filed May 18, 10 1906, which application is a continuation of my application, Serial No. 122,381, filed by me September 6, 1902, which in turn is a continuation of my application filed October 24, 1894, Serial No. 526,856.

Warp threads lying side by side and not under tension tend to cling to each other to some extent. This fact, especially in view 20 of their small diameter, renders it difficult to separate threads singly and in succession from a mass of threads.

The art or process herein disclosed includes a method of separating individual threads from a mass of threads consisting in 25 the following steps: first, arranging the threads in a sheet; second, stretching the sheet; third, deflecting the threads or sheet of threads; and fourth, releasing individual threads singly and in succession from their deflected position. When a thread is so released, its tension causes it to spring into or toward a straight line, the thread thereby separating itself from the remaining threads.

35 The process herein disclosed also includes a method of preparing a warp for the performance of operations on individual threads of the warp, consisting in the four steps above outlined and the additional step 40 of cutting the released threads singly and in succession. In this way, loose ends quite separated from the body of warp threads are provided for drawing into a loom element, for tying to similar threads of another warp, and for other purposes.

In the accompanying drawings, Figure 1 is a fragmental vertical sectional view of a 45 warp-drawing machine which may be employed in practising my invention. Fig. 2 is a fragmental horizontal sectional view

taken in the plane of dotted line 2—2 of Fig. 1. Fig. 3 is a fragmental detail view of a thread-deflecting member comprised in said machine. Fig. 4 is a front elevation of a warp frame also comprised in said machine. Fig. 5 is a fragmental view of one of the warp clamps of said frame. Fig. 6 is a fragmental perspective view of one of the bars used in inserting threads into said clamps. Figs. 7, 8 and 9 are views illustrating successive positions of the thread-selector and the stripper.

55 While any suitable means may be employed in practising the methods constituting this invention, I have herein shown the warp holding, selecting and severing means of a warp-drawing machine of the type fully illustrated and described in Patent No. 1,115,399, granted to me on October 27, 1914. Inasmuch as reference may be had to 60 said patent for a full understanding of the construction and operation of all of the mechanisms of said machine, I will herein describe only those parts which are directly related to the methods herein claimed. The 65 reference characters herein used are similar to those employed upon corresponding parts of the machine shown in said Patent No. 1,115,399.

70 The ends of the warp threads (from the warp beam, not shown) to be drawn into the eyes of the harness and through the spaces of the reed, are supported in a carriage B adapted to rest upon a rotatory screw-threaded shaft or carriage-adjusting element B¹, and arranged to be fed transversely of the thread-selecting mechanism by the intermittent rotation of said screw-threaded shaft. The carriage B leans against a short stationary ledge A¹⁹ (Figs. 1 and 7) 75 which is carried by the standard A¹⁸. The warp carriage comprises a frame having a longitudinal bar B² slightly above its center, two clamps B³ and B⁴ at its upper and its lower side, and the transverse frame-arms 80 B²³. The warp threads pass upwardly across the face of the carriage between the two clamps B³ and B⁴. The threads are bowed outward slightly from a right line by the protruding bar B². The clamp B³ 85

90

95

100

at the upper side of the carriage is pivotally connected with the frame of said carriage, and is susceptible of a slight swinging movement relative to the frame of the carriage and the clamp B⁴. This movement of the clamp B³ is effected by means of the links B⁵ (Fig. 4) pivotally connected at their opposite ends with arms B¹⁸ fixed on an oscillatory shaft B¹⁹ and with ears B²⁰ projecting from the clamp B³, respectively. The oscillatory shaft B¹⁹ is arranged to be moved by hand levers B⁶, fixed on the ends of said shaft. By means of the hand levers B⁶ and their connections just described the clamp B³ may be moved away from the clamp B⁴ sufficiently to draw the warp threads on the carriage taut between said clamps and bowed intermediate their ends over the bar B².

20 Each of the clamps B³ and B⁴ comprises two clamping jaws B⁷ and B⁸ faced with rubber, and an intermediate bar B⁹ against which the rubber-faced clamping jaws are closed, by which intermediate bar the warp threads are pressed downward between the clamping jaws. The clamping jaw B⁷ is movable toward and away from the jaw B⁸ by means of the inclined teeth B¹⁰ formed upon its rear face, which teeth correspond with the teeth B¹¹ upon a slidable locking bar B¹², which locking bar is longitudinally movable by means of the toggle hand lever B¹³ pivoted at B²⁴ (Fig. 5) to the frame of the clamp and connected by a link B²⁵ to the slidable bar B¹².

Assuming the clamping jaws B⁷ and B⁸ to be open (as in Fig. 5), the operation of clamping the warp is as follows: The warp is laid across the clamp, and the bar B⁹ is 40 pressed against the warp to carry the threads into the space between the jaws B⁷ and B⁸. The hand lever B¹³ is then swung (to the left in Fig. 5), thus moving the bar B¹² to the left, and thereby forcing the jaw B⁷ against the threads and the bar B⁹, whereby said bar B⁹ and the warp threads are secured in the clamp. The toggle lever B¹³ throws "over center" to hold the clamp closed.

50 In a groove in the edge of the bar B² over which the warp threads extend is a thin bar B¹⁴ (Fig. 1) slightly roughened upon its outer edge (Fig. 3). The bar B¹⁴ is longitudinally movable in said groove by means of a lever B¹⁵ (Fig. 6) pivotally connected with one end of said sliding piece and pivotally supported upon the bar B². The purpose of the slidable bar B¹⁴ is to slightly deflect the threads sidewise after 55 they have been clamped and stretched in the warp carriage so that when each individual warp thread is lifted from the roughened edge of the bar B¹⁴ by the selector (to be later herein described) the tendency of said thread will be to straighten and move away

from the body of warp threads, thus assisting in the separation of the threads. The threads are selected from what may be termed the concave edge of the warp, that is to say, the side away from which the threads are bowed.

The thread-selecting mechanism (Figs. 7, 8 and 9) comprises an arm H. By means of the mechanism described in said Patent No. 1,115,399, the upper end of the arm H 75 is given a motion somewhat triangular in outline, said arm moving forward toward the warp threads, sidewise away from the body of warp threads, and diagonally backward to the first position.

80 A stem H¹³ (Fig. 7) is pivotally mounted in the upper end of the arm H. Fixed to said stem is a yoke H⁷ in which is pivoted a shaft H²¹. To the shaft H²¹ is fixed a selector H⁸. A torsion spring H⁶ anchored at one end to a part fixed to the yoke H⁷ and attached at its other end to an arm H²² fixed on the shaft H²¹ presses the selector H⁸ toward the warp.

H¹⁰ is a stop screw carried by the arm H²² 90 and adapted to impinge upon the yoke H⁷ to limit the action of the spring H⁶.

The angle between the selector and a horizontal plane may be varied by means of an eccentric H¹¹ carried by an arm H¹² fixed to 95 the stem of the yoke H⁷, said eccentric acting upon the arm H.

The selector H⁸ is offset slightly toward the body of warp threads, and is provided on the side toward said threads with two or 100 more thread-hooks or pockets H¹⁵, the one near the forward end of the selector being smallest in size, and those rearward slightly larger, increasing from first to last. The purpose of these thread-hooks H¹⁵ is to 105 grasp a warp thread, and as it is necessary that only one warp thread be taken by the selector at each stroke thereof, the first hook is made of a size to receive a single small thread. If the first hook is too small to take 110 the thread presented, the second hook, being larger, probably will receive it; if not, the third. If the first hook was made large enough to receive a large thread, it sometimes would grasp two small threads, hence 115 the graduation in size of said hooks.

As hereinbefore explained, the warp threads extend across the roughened edge of the strip B¹⁴ and are deflected (toward the right, Fig. 2) out of a vertical plane. 120 Referring to Fig. 2, the selector H⁸ reciprocates transversely of the strip B¹⁴. As the selector moves forward, one of its hooks picks up the foremost warp thread. As soon as the thread is lifted out of contact 125 with the edge of the strip B¹⁴, the thread springs into or toward the vertical plane passing through the clamped ends of the thread, the selector yielding laterally against the tension of the spring H⁶. Con- 130

tinuing its forward movement, the selector carries the thread against a device I for guiding and releasably holding the thread, which device is fully described in my said patent. In the advancing movement of the selector, the thread is carried against a cutter disk, whereby the thread is severed and a free end thus provided for the drawing-in operation.

The thread-severing means above referred to comprises, in the present embodiment, a cutter disk J (Fig. 2) fixed near the upper end of a rotary shaft (not shown) which is mounted within a stationary sleeve J¹ fixed in the frame of the machine. The disk is covered by a housing J² open at one point to permit the thread to be pushed in the forward movement of the selector against the disk in order to sever said thread. A stripper H¹⁶ (Figs. 2 and 7) is fixed at the upper end of an oscillatory shaft H¹⁷ (Figs. 2 and 4) mounted in suitable bearings on the arm H. This shaft is oscillated and the stripper H¹⁶ moved forward and backward with relation to the arm H and the selector H⁸ by means of a connection between an arm H¹⁸ fixed to the lower end of said shaft and an arm H¹⁹ secured to a part of the supporting frame (see Fig. 2). The arms H¹⁸ and H¹⁹ have ball-and-socket connections with opposite ends of a connecting rod H²⁰, and thus when the arm H is moved forward the stripper also moves forward with relation to said arm. In the continuing movement of the arm H, the stripper H¹⁶ is caused to swing forward and take the thread from the selector, the thread then extending from the thread-holder I through a notch I¹⁰ (Fig. 9), through the hook of the stripper H¹⁶ to the upper warp clamp B³. The purpose of the stripper is to bring the thread to a definite and uniform position with reference to the needle, notwithstanding the fact that the thread may have been taken by any one of the selector hooks. The stripper also catches any selected thread that may escape from the selector.

A detaining finger I⁵ is pivotally mounted near the forward side of the device I and is yieldingly held forward against a stop I⁶ by means of a coiled spring I⁷. The finger I⁵ yields to allow the selected thread to pass it. The purpose of this finger is to hold back a second warp thread that may adhere to the one carried forward by the selector. To prevent such second warp thread from springing to the left (Fig. 7) so that the next hook of the se-

lector would catch it, I provide a stop shoulder w. 60

The various operations may be summarized as follows: A transverse section of the warp in the form of a sheet is first secured in the clamps B³ and B⁴; the sheet is stretched by means of the hand lever B⁶; the sheet is deflected by means of the hand lever B¹⁵; the threads are released from the deflecting bar B¹⁴, singly and successively, beginning at the concave edge of the warp, by means of the selector H⁸, the tension of the thread causing it to spring into or toward a straight line, and the thread thereby separating itself from the remaining threads; and the separated thread is moved by the selector into contact with the cutter disk J and severed, whereby a separated, loose thread is provided for the subsequent warp-drawing, warp-uniting or warp-leasing operation. 75

I claim as my invention:

1. In the process of handling warps preparatory to weaving, the step of separating individual threads from the warp consisting in stretching a section of the warp, deflecting the threads of said section, releasing individual threads in succession from their deflected position, and moving each released thread into position for the performance of another operation thereon. 80

2. In the process of handling warps preparatory to weaving, the step of separating individual threads from the warp consisting in stretching a section of the warp, deflecting the threads of said section, releasing individual threads in succession from their deflected position and moving each released thread into position for the performance of another operation thereon, and cutting the released threads singly and in succession. 90

3. In the process of handling a series of elastic elements preparatory to weaving, the step of selecting individual elements from the series consisting in deflecting or bowing the series to place the elements under tension, releasing individual elements in succession from their deflected position, whereby 100 when the elements are released they spring away from the deflected series, and moving each released element into position for the performance of another operation thereon. 105

Signed at Rockford, in the county of Winnebago, State of Illinois, this 17th day of December, 1906.

HOWARD D. COLMAN.
